UNITED STATES PATENT OFFICE.

WILLIAM K. RICHART, OF SCRANTON, PENNSYLVANIA.

DEVICE FOR APPLYING BELT-DRESSING TO BELTS.

SPECIFICATION forming part of Letters Patent No. 712,417, dated October 28, 1902.

Application filed January 4, 1902. Serial No. 88,464. (No model.)

To all whom it may concern:

Be it known that I, WILLIAM K. RICHART, a citizen of the United States, residing at Scranton, in the county of Lackawanna, State 5 of Pennsylvania, have invented certain new and useful Improvements in Devices for Applying Belt-Dressing to Belts, of which the following is a specification.

The purpose of this invention is to provide 10 a device for applying hard belt-dressing to belts; and it comprises a box or holder for the belt-dressing, a roller extending across an open end of the casing, and devices for forcing the belt-dressing against the roller, where- 15 by when the latter is rotated by contact with a moving belt the belt-dressing will be melted by the friction of the roller and transferred to the surface of the belt in a semiliquid state and soak into the outer part of the belt be- 20 fore becoming cooled and solidified.

In the accompanying drawings, Figure 1 is 25 a perspective view of the device. Fig. 2 is a plan view with the top of the casing removed, and Fig. 3 is a longitudinal central section through the device.

Referring to the drawings, A indicates a 30 casing comprising the sides 1 and 2, the top 3, and the bottom 4. As shown, the top and bottom are shorter than the sides, and jour- 35 naled between the forward ends of the sides upon a rod or shaft 5 is a roller 6, which closes the forward end of the casing. The roller is preferably made of wood having a smooth face. The sides 1 and 2 of the casing are 40 similarly constructed, each having a long longitudinal slot 7, said slots being parallel with one another, and a cross-bar 8 extends transversely through the casing and through the slots 7. The belt-dressing B, which is in 45 the form of a cake, generally having the consistency of soap, is arranged within the casing between the roller 6 and follower 9, the latter being arranged between the cross-bar and the rear end of the cake of dressing. 50 Coiled springs 10 and 11 are secured to the opposite ends of the cross-bar, and these springs are adjustably attached to the sides of the casing by means of wire pins 12, which engage or hook over studs 13 14, &c., ar- 55 ranged in pairs upon the sides of the casing. As shown, the pins 12 are formed with cen-

tral loops 15 for attachment to the forward ends of the springs.

In operation when it is desired to apply belt-dressing to belts, the latter being in motion, the device is held with the roller bearing upon the belt. The roller is thereby rotated, and sufficient heat is generated by the friction of the roller upon the dressing to melt the latter, which is then carried out upon 60 the roller and deposited in a semiliquid state upon the belt. As the cake of dressing wears away the follower moves it forward by the force of the springs. As the cake shortens the attaching-pins 12 may be moved forward 65 and hooked over the succeeding pairs of studs, thus adjusting the tension of the springs. It is also desirable to provide devices by which the tension of the springs may be adjusted in order to apply greater pressure to very hard 70 dressing than to softer material.

The surface of the roller should not be rough enough to grind or tear the belt-dressing, and it should not be smooth enough to slip upon the dressing without causing sufficient friction to melt or partially melt the material. A smooth hard wooden roller is found in practice to answer the purpose very satisfactorily. The cake of belt-dressing may be inserted within the casing by removing the 80 top 3 or by loosening the springs and with- drawing the cross-rod 8 and follower 9.

What I claim as new, and desire to secure by Letters Patent, is—

1. In a device for melting hard belt-dressing and applying said dressing in its softened state to belts, a casing adapted to contain a cake of belt-dressing, a smooth roller extending across one end of the casing and adapted to be applied to the belt, and a spring-pressed 85 follower within the casing arranged to force the cake of dressing against the roller.

2. In a device for melting hard belt-dressing and applying said dressing in its softened state to belts, a casing adapted to contain a 90 cake of belt-dressing, a smooth wooden roller extending across one end of the casing and adapted to be applied to the belt and a spring-pressed follower within the casing arranged to force the cake of dressing against the roller. 95

3. A casing adapted to receive a cake of belt-dressing, said casing being open at its

forward end and having longitudinal slots in its sides, a roller journaled between the sides of the casing and extending across the opening, a follower within the casing adapted to hold the cake of belt-dressing against the roller, a cross-bar in the rear of the follower and projecting through the slots in the sides of the casing, and springs connecting the ends of said bar to the casing and adapted to force the rod against the follower.

4. A casing adapted to receive a cake of belt-dressing, said casing being open at its forward end and having longitudinal slots in its sides, a roller journaled between the sides of the casing and extending across the open-

ing, a follower within the casing adapted to hold the cake of dressing against the roller, a cross-bar in the rear of the follower and projecting through the slots in the sides of the casing, springs connected to the ends of said cross-bar, studs upon the sides of the casing arranged in pairs at different distances from the forward end, and pins upon the free ends of the springs adapted to hook oversaid studs. 20

In testimony whereof I affix my signature 25
in presence of two witnesses.
